UNITED STATES PATENT OFFICE.

LOUIS F. ERHART, OF CINCINNATI, OHIO, ASSIGNOR TO THE THOS. J. CORCORAN LAMP COMPANY, OF CINCINNATI, OHIO, A CORPORATION OF OHIO.

LAMP-CLOSURE FASTENER.

Application filed April 20, 1926. Serial No. 103,276.

This invention is particularly designed for lamps of the type used on automobiles and relates to a means for securing the door or closure on the body of such lamps, a particular object being to produce a closure fastener in which a dust proof, moisture proof and vibrationless closing of the reflector and glass or lens covering elements is secured with a simple, neat, easily operated, cheap and substantial embodiment of cooperating elements.

These and other objects are attained in the fastener described in the following specification and illustrated in the accompanying drawing in which:

Fig. 1 is a sectional elevation of an automobile lamp equipped with a fastener embodying my invention.

Fig. 2 is a front elevation of the lamp shown in Fig. 1, certain parts having been shown broken away and in section for clearness of illustration.

Fig. 3 is a somewhat enlarged fragmental sectional view showing one position in the operation of the fastener shown in Figs. 1 and 2.

Fig. 4 is a view the substantial duplicate of that shown in Fig. 3, but disclosing the position assumed by the parts upon completion of the fastening operation.

Figs. 5, 6 and 7 are views similar to Figs. 3 and 4, but upon reduced scales and showing modifications of the fastener shown in Figs. 1 to 4 of the drawing.

The lamp to which my improved fastener has been applied, consists of the usual body 8 which contains a reflector 9 supported upon the body rim 10 at the open end of the body, a lamp bulb 11 being located within the reflector and a lens 12 closing the reflector mouth, with a closure rim 13 over the open end of the body for holding the lens in position. A packing or cushion ring 14 is provided on the reflector to enable the lens to close it against dust and moisture when the rim 13 is clamped in position.

At the open end of the lamp body a grooved flange 15 is formed. This flange, as shown in the four main figures of the drawing, is inwardly curved in somewhat semicircular form, although it may partake of other shapes as shown in Figs. 5, 6 and 7 and as will be described. The closure rim 13 is preferably formed with a turned over or hooked rear edge 16 which carries the rear

edge of a band 17 which is shaped to substantially fit the shape of the groove 15 of the body. This band is free of the closure rim and is somewhat yielding not only throughout its length, but also transversely as represented by its cross section shown in Figs. 1, 3 and 4. The band is not continuous, that is, it has two ends which carry lugs 18 and 19. These lugs extend through a slot 20 in the rearward flange 21 of the door rim, so that by means of a screw 22 they may be drawn toward each other, thereby tightening the band about the body grooved flange 15 and making the band tend to fit more perfectly within the body groove.

Owing to the cushion effect produced by the packing 14, the first position taken by the closure when the rim 13 is placed over the open end of the body and then pressed back so as to cause the band 17 to just begin to enter the groove 15, is that shown in Figs. 1 and 3. However, when the screw 22 is tightened, the ends of the band are drawn toward each other, thereby contracting the band and bringing its inclined surface and that of the groove at or about the point 23, into intimate relationship to cause sliding action of the band surface over the groove surface. This causes the rear edge 24 of the band to press upon the hooked rear edge 16 of the closure rim, thereby drawing or forcing it backwardly, allowing the band curvature to more nearly fit that of the groove as shown in Fig. 4, as well as causing the packing ring 14 to be compressed as shown in Fig. 4, to completely seal the reflector. It will thus be seen that the forward or free edge of the band may yield upon the rim flange 21 as the band becomes subjected to different conditions of tension or shape, but that the rear edge of the band will be held by the hooked rear edge of the rim to cause it to be pushed or drawn backwardly.

In Figs. 5, 6 and 7, I have shown that the shape of band and cooperating groove as disclosed in Figs. 1 to 4 inclusive, need not be strictly adhered to in order to produce the results desired and within the scope of the field of novelty of the invention I am setting forth herein. For example, in Fig. 5 I have shown a band 25 and cooperating groove 26 which are of substantial V shape. It is quite obvious that such a construction will produce the same results secured by the

form shown in Figs. 1 to 4 inclusive and that the manner in which operation is secured is identical. In Fig. 6 I have shown a form of band 27 and groove 28 having but 5 one incline. This however does not alter the function or operation of the device in any manner. This is also true of the form shown in Fig. 7 which is quite similar to the first described form of the invention.

10 Here the band 29 and groove 30 are merely provided with lipped edges to facilitate freedom of sliding action of the band over the rearwardly extending flange of the closure rim as the transverse shape of the band is 15 changed upon operation of its clamping means. It is also quite obvious that any suitable means may be employed for drawing the ends of the band toward each other in order to produce the necessary clamping 20 action.

And now, in addition to the features which I have set forth, there is an added feature obtained in providing the band 17, 25, 27, and 29 with the necessary number of 25 glass clips which will hold the closure glass 12 in place on the closure rim, after the manner disclosed by the clips 31 shown in Figs. 2, 3, and 4. These clips are secured to the band by soldering, rivets or other 30 suitable manner. These clips are so shaped

at their free ends that they press yieldingly upon and in hooked relation with the closure glass to retain it in position in the closure rim. The particular advantage of such a unit construction of glass clips and contractible band lies in the rapidity with which 35 closure rim, glass, band and clips may be assembled by but substantially a single operation, namely, the placing of the band within the closure rim. 40

Having thus described my invention what I claim is:

An automobile lamp comprising a body having an open end, a reflector mounted within the open end of the body, a glass 45 closing the reflector, and a hollow closure rim having an abutment on its rear edge formed by turning its rear edge inwardly, said rim closing the body and adapted to hold the glass in position, said body having a groove inclined toward the rear adjacent to the open end, a contractible band occupying the hollow of the rim, in normal engagement with the rim abutment, and means adapted to contract the band about the body 50 and into the groove. 55

In testimony whereof I have hereunto affixed my signature.

LOUIS F. ERHART.
